DESIGN FOR AN OIL BURNER

Henry H. Yerk, Davenport, Iowa

Application July 27, 1934, Serial No. 52,715

Term of patent 7 years

To all whom it may concern:

Be it known that I, HENRY H. YERK, a citizen of the United States, residing at Davenport, in the county of Scott, and State of Iowa, have invented a new, original, and ornamental Design for an Oil Burner, of which the following is a specification, reference being made to the drawings, forming a part hereof.

In the drawings, Figures 1 and 2 are perspective views and Figure 3 is a plan view of an oil burner embodying my invention.

I claim:

The ornamental design for an oil burner as shown.

HENRY H. YERK
